UNITED STATES PATENT OFFICE.

ALBERT H. CARRIER, OF ASHEVILLE, NORTH CAROLINA, ASSIGNOR OF ONE-HALF TO
EDWIN W. GROVE, OF ST. LOUIS, MISSOURI.

SHELTER FOR OUTSIDE SLEEPING-BEDS.

1,360,883.

Specification of Letters Patent. Patented Nov. 30, 1920.

Application filed January 3, 1920. Serial No. 349,294.

To all whom it may concern:

Be it known that I, ALBERT H. CARRIER, a citizen of the United States, residing at Asheville, in the county of Buncombe and State of North Carolina, have invented new and useful Improvements in Shelters for Outside Sleeping-Beds, of which the following is a specification.

This invention relates to outside sleeping inclosures or shelters. The improved inclosure or shelter is particularly adapted for use by sick persons and especially tubercular patients who are frequently too weak to open and close windows comprised in the organization of outside sleeping inclosures or shelters, and the primary object of the invention therefore is to provide comparatively simple and readily operable means whereby an occupant may close communication between the inclosure or shelter and an adjacent room and simultaneously open the inclosure or shelter to the outside air, or vice versa, while lying in a prone position and by exercise of very little effort through the medium of an easily operating counterbalanced single communication controlling device mounted to swing in opposite directions over the inclosed occupant.

The invention consists in the construction and arrangement of the several parts which will be more fully hereinafter described and claimed.

In the drawings:—

Figure 1 is a longitudinal vertical section of an inclosure or shelter embodying the features of the invention.

Fig. 2 is a transverse vertical section of the same.

Fig. 3 is a perspective view of parts of the improved structure.

The numeral 5 designates an outside wall suitably secured and sustained in safe fixed position relatively to a building wall 6 adjacent to a window opening 7 defined by a frame 8 in the latter wall. The outside wall has a suitable ceiling or covering 9 and a bottom 10 which may be in some instances a porch floor constructed in the usual manner. The wall 5 has a window opening 11 defined by a frame 12 and in transverse alinement with opening 7 and frame 8. The sills 13 and 14 of the respective frames 8 and 12 are in reverse positions, the sill 13 of frame 8 having its stop shoulder 15 at the inner part thereof, as shown by Fig. 2. The im-

proved inclosure or shelter also has similar end walls 16 extending fully from the ceiling or covering 9 to the bottom 10, and at a distance inwardly from the two end walls are supplemental walls 17 of less vertical extent than the walls 16 and secured to horizontal supports or sills 18 between the outer wall 5 and wall 6. The width of the space between the walls 16 and 17 may be varied at will and as may be found necessary and the supports or sills 18 will be strongly secured in fixed positions by any preferred means, both supports or sills being at the same elevation above the bottom or floor of the inclosure and having their upper edges flush with the upper edges of the walls 17 as shown by Fig. 1. The walls 17 also preferably extend the full interior width of the inclosure or shelter and provide head and foot boards of a bed 19 comprising rails or supports 20 between and terminally held by the walls 17 and having slats 21 and a mattress 22 and other suitable bed accessories and equipments. The construction of the bed is immaterial and may be modified, but in all forms of the bed that may be used the essential feature is to adopt a simplified and economical structure or one that may be erected within the inclosure and adapted to remain in fixed position; yet the invention is not limited for use with a fixed bed structure and in some instances the bed structure, if desired, may be of the movable bed type temporarily retained against movement or having sufficient weight to maintain its proper position within the inclosure or shelter.

The most essential feature of the invention is a sensitively operable sash 23 mounted to swing over a person or patient in prone position in the bed and to engage and alternately open and close either opening 7 or 11, and when this sash is closed it will form a tight joint with either the sill 13 or 14 and reversely engages the said sills and also with either of the usual stops 24 or 25 at the tops of the window frames 8 and 12 and also with either of the usual stops along the sides of the said frames. The sash 23 will be generally constructed as an ordinary window sash and has secured at the center of each end a metal frame 26, said frames comprising toothed segments 27, each of the frames 26 with its segment 27 being preferably of cast integral construction, though

it may be formed in any other manner or be composed of separate parts. The toothed segments 27 are mounted to have a rolling action relatively to racks 28, each having 5 a channel 29 opening through the top thereof with the rack teeth 30 formed in the bottom wall of the channeled, as shown by dotted lines in Fig. 2. The racks 28 are secured on the intermediate portions of the 10 upper edges of the walls 17 and the supports or sills 18 and have their inner sides flush with the inner sides of the said walls 17 and their outer sides flush with the outer sides of the said supports or sills. Secured to the outer side of the lower portion of 15 each frame 26 is an angular hanger 31 having a segmental counterpoise weight 32 attached to the lower ends of the members thereof as clearly shown by Fig. 3. The 20 hangers 31 and counterpoise weights 32 fixed thereto have unrestricted movement in the space between the walls 16 and 17 during the operation of the sash, the said hangers standing outwardly a sufficient distance to fully clear the outer sides of the 25 supports or sills 18. The sash 23 also has arms 33 secured to opposite ends thereof adjacent to the sides, there being a pair of these arms at each end of the sash, and to 30 the free ends of the said arms 33 flexible pull cords or straps 34 are attached and have grips or stirrups 35 secured to their free ends, the cords or straps 34 and grips 35 having a length sufficient to dispose them 35 within easy reaching distance of the occupant of the bed and also provide for a disposition of the occupant of the bed with his head at either end of the latter. In other words, the sash may be operated from either 40 extremity and without requiring the occupant of the bed to arise to a sitting posture or requiring any material amount of strength or exertion in disposing the sash as may be desired in any one of its positions. Instead of operating the sash to 45 alternately open and close the window openings 7 and 11 it may be permitted to rest in horizontal position, as shown by Fig. 2, especially under weather and temperature 50 conditions when it is desired that ventilation be provided through the opening 7.

The segments 27 and racks 28 will be maintained in their operative association against accidental displacement under ordinary actuating conditions without additional confining means or devices to obstruct their separation. However, to provide for possible contingencies and to guard against dissociation of these segments and 55 racks even under unusual strenuous action, guard sills or strips 36 are secured at a suitable elevation above the racks 28 and the frames 26 and segments 27 have outwardly projecting pins 37, one to each group of

frames and segments to movably bear 65 against the said sills or strips 36, the latter being of wood and having metal wear strips 38 secured against their lower edges. By this means the segments and racks are confined in operative relation and prevented 70 from having any tendency to become disengaged.

From the foregoing the operation of the improved sash will be readily understood, but to give a brief résumé of the operation, 75 the occupant of the bed by the use of one hand may pull on the righthand arm 33 as shown by Fig. 2, through the medium of the cord or strap 34 and grip 35 and thereby cause the sash to turn inwardly and close the 80 opening 7, or conversely the lefthand arm 33, cord or strap 34 and grip 35 may be similarly pulled to close the opening 11, the latter opening being closed as will be understood when the weather is too sever, or to prevent 85 exposure of the patient or occupant of the bed. At other times, as hereinbefore indicated, the patient may dispose the sash in a horizontal position and thereby permit a circulation of air through both the openings 90 7 and 11. During the operation of the sash, the toothed segments 27 will roll in mesh relation to the teeth 30 of the racks 28 and will be retained in operative position by the formation of the channels 29, the said 95 toothed segments and their frames 26 being disposed in either one of the two dotted positions as shown in Fig. 2 when the sash is operated to close either the opening 7 or 100 11, or the said frames and toothed segments will then be in planes at right angles to the positions occupied by the same frames and segments when the sash is in horizontal position over the occupant of the bed. In all of the positions that may be assumed by the 105 toothed segments 27 relatively to the racks 28 the teeth of the segments and the racks are always in position for instant and positive engagement and by this means the sash is prevented from slipping out of place, and 110 as a means for holding the sash in place the hangers 31 and counterpoise weights 32 are used. A further advantage of the improvement is that by use of the frames 26 and segments 27 as carrying means for the sash, the 115 sash takes a higher level in its travel over the bed by reason of the shape of the said frames and segments, and should a patient be in a sitting position will move clear over his head.

The foregoing construction will be found exceptionally advantageous in its operation and service, or in the performance of its intended functions, and may be readily installed at a comparatively small expense.

What is claimed as new is:—

1. The combination with a wall having a window opening and an outside inclosure

also having a window opening in alinement with the opening of the said wall, of a single sash mounted to close one window opening and clear the other opening or to be disposed between the two openings whereby either one or the other of the window openings may be opened or closed or both openings remain simultaneously open.

2. The combination with a wall having a window opening and an outside inclosure having a window opening in its outer wall in alinement with the first mentioned window opening, and means operable to alternately close and clear the respective window openings.

3. The combination with a wall having a window opening therein and an outside inclosure with an outer wall having a window opening therein, the inclosure adapted to have a bed mounted therein, and a single sash mounted to rotate over the bed and close either one of the openings or to be disposed between the two openings and leave the latter both clear of closing means whereby a reclining occupant of the bed may operate the sash as desired.

4. The combination with a wall having a window opening and an outer inclosure with a bed therein and also having an outer window opening in alinement with that of the said wall, and a single sash provided with counterpoise means and devices for swinging and overturning the same above the bed to engage either window opening or for dis-

posing it between the two window openings to leave the latter clear of the sash.

5. The combination with a wall having a window opening therein and an outer inclosure having an outer wall with a window opening therein in alinement with the first opening, the inclosure adapted to have a bed disposed therein, of a single sash mounted to move over the bed to alternately engage either window opening, the sash having toothed segments and counterpoise means and pull devices connected to opposite ends thereof, and horizontal grooved racks with which the toothed segments engage.

6. The combination with a wall having a window opening therein and an outer inclosure having an outer wall with a window opening therein in alinement with the first opening, the inclosure adapted to have a bed disposed therein, of a sash mounted to move over the bed to alternately engage either window opening and provided with toothed segments, racks with which the segments have a loose rolling engagement, and means for preventing the accidental disengagement of the segments from the racks.

In testimony whereof I have hereunto set my hand in presence of two subscribing witnesses.

ALBERT H. CARRIER.
